ELECTRIC FUSE

Application filed February 28, 1928. Serial No. 257,598.

This invention relates to improvements in electric fuses, and has particular reference to a fuse of the type employed in electric circuits for the purpose of protecting the same against 5 overloads.

An object of the invention is to provide an improved fuse of simple, practical and inexpensive construction wherein the fusible element employed may be easily and quickly re-10 moved and replaced.

Another object is to provide the body of the fuse with a tapered bore extending the entire length thereof and to utilize a similarly shaped plug to secure or wedge a fusible element in the bore, said plug projecting beyond the ends of the body, when the fusible element is secured in position, so that by tapping the smaller end of the plug the same may be loosened preliminary to its withdrawal from said 20 body and subsequent removal of the fusible element.

The above and other objects will appear more clearly from the following detailed description, when taken in connection with the 25 accompanying drawing, which illustrates a preferred embodiment of the inventive idea.

In the drawing—

Figure 1 is a side elevation of the fuse constructed in accordance with the invention; 30 Figure 2 is an enlarged longitudinal section thereof;

Figure 3 is a section on the line 3—3 of Figure 2;

Figure 4 is an end elevation; and

Figure 5 is a perspective view of the fusible element.

Referring more particularly to the accompanying drawing, the numeral 6 indicates the body of the fuse which is made of any suitable 40 insulating material, such as vulcanized fibre or the like. This body is cylindrical in cross-section and is provided with a longitudinal bore 7 extending the entire length of the body and of slightly tapered formation through-

45 out. The tapering of the bore may, however, be dispensed with. Each end of the body 6 has mounted thereon an electric terminal or head 8 recessed at its end to receive the adjacent end of said body. To secure the terminals 8 to the body, the inner end of each ter-

55 minal may be inturned, as indicated at 9, to extend into an annular groove 10 formed in said body. Each terminal is also provided with a central tapered opening 11 aligned with the bore in said body.

The fusible element 12 is of a standard type and when inserted into position in the body 6 its ends will engage the terminals 8 so as to complete the electric circuit. The ends of the element 12 may project beyond the ends of the 60 terminals and, in order to prevent shifting of the element in the body, when securing the former in position, the end of said element adjacent the larger end of the bore 7 may be bent laterally, as indicated at 13, and engaged 65 with the terminal so as to form a stop which limits the movement of said element 12 toward the other end of the body.

To fix the fusible element 12 in position 70 with its ends in contact with the terminals 8, there is provided an insulated plug 14 tapered longitudinally throughout its length and capable of insertion into the bore of the body. In so doing, the plug will wedge the element 12 in position, as shown, and cause the same 75 to assume a cross-sectional contour conforming to those of the body and terminal members thereby securing intimate contact therewith, it being understood that said element 12 is made of malleable metal. The plug 14 is 80 longer than the combined lengths of the body 6 and terminals 8 so that the ends of the plug will project beyond said terminals when the plug is in wedging position. Thus said ends are easily accessible either for the purpose of 85 striking the larger end thereof to increase the wedging action or for loosening the plug by tapping upon the smaller end. It is obvious that the latter operation can be easily and quickly accomplished in the event of the 90 fusing of the element 12, whereupon the defective element may be extracted and a new one fixed in its place.

What is claimed is:

1. An electric fuse including an open ended body of insulating material having a bore therethrough, terminal members carried by the ends of said body, a fusible element contacting the wall of said bore and engaging 95 said terminal members, and a tapered insu- 100

lated plug extending through said bore and wedging said fusible element against said wall.

2. An electric fuse including an insulated body having a bore extending the entire length thereof, terminal members at the ends of said body having openings aligned with said bore, a fusible element extending the length of said bore and having its ends engaged with said terminal members, and an insulated plug projecting through the openings in said terminal members and said bore to secure said fusible element in engagement with said members.

3. An electric fuse including an insulated body having a tapered longitudinal bore extending its entire length, end terminal members secured to said body and having tapered openings aligned with said bore, a fusible element extending through said bore and having its ends engaged with said terminal members, and an insulated tapered plug projecting through said openings and bore to engage said fusible element and wedge it into intimate contact with said terminal members, the ends of said plug extending outwardly beyond the outer ends of said terminal members.

4. An electric fuse including an insulated body having a bore extending therethrough, and terminal members having tapered openings the walls of which are aligned with and form continuation of said bore, a fusible element extending through and contacting the walls of said openings, and a tapered plug projecting through said bore and openings to bind said fusible element against the walls of the latter.

5. An electric fuse of the cartridge type including an insulated body having a tapered bore, terminal members at the ends of said body, a fusible element extending through the bore in said body and engaged with said terminal members, and a tapered plug in said bore for wedging said fusible element against the wall thereof, the ends of said plug projecting outwardly beyond said terminal members and being exposed to permit tapping at either end when removing or wedging in position the fusible element.

6. In testimony whereof we have affixed our signatures:

WILLIAM H. HUMPHREYS.
WILLIAM J. POLLOCK.
